UNITED STATES PATENT OFFICE

DAVID E. ANDERSON, OF ST. PAUL, MINNESOTA

METHOD OF PRODUCING FILLERS FOR RAILROAD FROGS

Application filed September 1, 1928. Serial No. 303,380.

- My invention relates to the method of producing rolled steel fillers by bending the fillers to suit the sections of rails with which the fillers are to be used, and then planing or cutting the fillers the desired shape to provide a sufficient shoulder under the rail which consists in the beveled point such as is used in my Patent No. 1,580,108. This method permits the manufacture of fillers in an economical manner and in some cases is to be preferred over the solid cast fillers such as are used in my patent hereinbefore mentioned. By first bending the rolled steel filler, as will be hereinafter more fully described, and then cutting the same into the desired shape, a shoulder is provided which extends under the beveled point clear to the tip of the same and a filler can be built up from ordinary straight rolled steel fillers capable of supporting the frog point and the rail sections in a practical manner so that the fillers are capable of supporting the load and provide a strong, efficient means of filling in between the frog point and the side and guide rails.
- The objects and features of my method will be more fully hereinafter described, together with other important details of the same.
- To assist in describing my method I have shown in the drawings:
- In Figure 1 I have illustrated a plan view of my rolled steel fillers made by my method as they would appear used in conjunction with my frog point, of the type set forth in my patent hereinbefore mentioned.
- Figure 2 is a plan view of the two fillers used on either side of the frog point, showing the fillers bent as is accomplished in carrying out my method, and showing in dotted outline their straight position before they are bent.
- Figure 3 is a plan view of the finished fillers, only a portion of which is illustrated, after they have been bent and cut away or planed in the desired shape.
- Figure 4 is a section approximately on the line 4—4 of Figure 1, in the direction of the arrow, showing the manner in which the fillers support the frog point clear down to the tip as well as the side rails.
- My method consists in producing fillers for

rails and frog points such as are illustrated in my patent hereinbefore mentioned in an economical manner. The cast fillers are, under present conditions, somewhat more expensive than the fillers which are made by the method herein described, and it is thus important to consider that the fillers herein set forth are desirable for certain uses in conjunction with railway rails and particularly frog points and guide rails where a more expensive frog point might be prohibitive and where the wear and tear on the point is of a lesser nature than in some cases.

In carrying out my method I employ rolled steel fillers A and B, one of which is used on one side and the other on the other side of a frog point such as C. The frog point C herein described is of a construction of the nature which is set forth in my patent hereinbefore mentioned, having shoulders 10 on each side of the same right down to the very tip portion thereof.

The rolled steel fillers A and B are ordinarily of a straight nature from end to end and as illustrated, the straight formation on one end in dotted lines 12, such as in Figure 2. The full lines in this figure show the bending of the end 13 of the rail A to one side of the straight formation, while the rail B is illustrated with its end 14 in full lines bent out of line with the straight line formation as is illustrated by the dotted lines 12.

The first step of my method resides in the bending of the fillers A and B as indicated in the plan view in Figure 2. The dotted lines 12 show the original shape and position of the fillers before they are bent.

The fillers A and B are illustrated in cross section in Figure 4. These fillers have a thick central body portion 15 and the cross section shape is virtually similar to an I-beam. The fillers A and B are provided with flange members 16 on either side which are adapted to fit beneath the shoulders 10 and beneath the shoulders 17 of the head 18 of the side rails 19 and 20. After the rails A and B have been bent with the offset portions 13 and 18 respectively, as illustrated in Figure 2, the method is further carried out by planing the rail A with the recess portion 22 and also the

recess portion 23. These recesses are cut into the flange 16 as illustrated in the plan view in Figure 3 of the filler A. The filler B is planned away along the web 16 at 24 so as to 5 form the longitudinal opening 25 between the fillers A and B which is adapted to receive the upstanding web 26 of the frog point C when the fillers A and B are connected together by the bolts 27, as illustrated in Figure 1.

In the drawings I have illustrated the fillers A and B associated together in Figures 2 and 3 in their relative position one to the other, so that they may be more easily 15 comprehended in their use and in the position that they assume when put together in use with the frog point C and the side rails 19 and 20.

It will be noted that by bending the rails 20 A and B, as illustrated in Figure 2, and then planing the rails to cut away the longitudinally extending recess 22 and also the longitudinally extending recess 23 on the side of the filler A adjacent the side of the filler B 25 which is cut away along the longitudinal portion 24, that the fillers A and B are made in the desired shape to carry out the principles of my method. The recess 25 between the fillers A and B receive the web 26 of the point 30 C, while the recess 22 is adapted to receive the point D of the rail 28, illustrated in Figure 1.

In Figure 3 I have illustrated in dotted lines the outer portion of the fillers A and B 35 which are planed away so that the side rails 19 and 20 can fit up against the flange members 16 of the respective fillers A and B to provide the desired positioning of the side rails 19 and 20 in relation to the frog point C. 40 The rails 19 and 20 are beveled away at 29 and 30, respectively, to properly shape the sides of the same to form the guard rails back along the rail 28 and the rail forming the frog point C.

The fillers A and B act to provide a rigid support between the sides of the rails 19 and 20 and the frog point C which is made up of two rails with the points C and D inclined together. It is important that the fillers be 50 shaped to the inside curvature of the rail which forms the frog point C such as the web portion 26 and the similar webs of the rails 19 and 20, as illustrated in Figure 4. This 55 provides a very substantial and secure supporting means for the shoulders 10 of the tip end of the frog C and by accomplishing this in the manner of the method set forth, I provide an economical filler, readily made up and 60 very practical in use.

Thus the method consists in taking a pair of filler members such as A and B and bending them to diverge away from each other at the desired angle to fit the occasion of the fitting together of the frog point and side rails,

and then planing the outside surfaces of the fillers to conform with the angle and shape of the guard and side rails 19 and 20, and cutting the inside surfaces of the respective fillers which extend adjacent each other out in a manner to receive the frog point proper and the supplemental rail point to cause the fillers to fit in close relation to the sides of the frog point, supplemental rail point and the sides of the guard rails.

In accordance with the patent statutes I have described the principles of my method and while I have set forth a particular means of carrying out the same and while I have only 70 diagrammatically illustrated members which are adapted to carry out the principles and steps of my method, I desire to have it understood that variations may be made within the scope of the following claims without departing from the purpose and intent of the 75 method set forth.

I claim:

1. The method of forming fillers for a frog point and guard rails consisting in bending a pair of filler members in a manner to diverge away from each other at one end the desired degree, then cutting away the inner sides of said fillers to fit closely to the sides of the frog point and supplemental rail point, and then cutting away the outer sides of said 90 fillers to cause the same to fit the angle and formation of the side rails of the frog when the fillers are clamped together with the frog point and rail point therebetween and the side rails bolted to the outer sides of the filler.

2. The method of forming fillers for frogs consisting in bending I-cross-sectional shaped filler members to diverge away from each other, then cutting said fillers on the adjacent 95 inside surfaces to fit closely the surface of the frog point and rail from beneath the side shoulders of the point to the base flange of the same, and then forming the outer surfaces of said fillers to fit the guard rails to 100 provide a built-up frog filler.

3. The method of producing a filler for a frog point with shoulders to the very tip of the point consisting in forming rolled steel fillers with the inner faces to conform with the shape of the frog point at the sides, and forming the outsides of the filler members to the shape and angular position of the side 115 guard rails.

4. The method of producing a filler for railroad frogs consisting in shaping a pair of rolled filler members with the inner surfaces to conform with the outer surfaces of the frog point and connecting rail, and the outer surfaces of the filler members to conform with the inner surfaces of the guard rails on either 120 side of the frog point.

5. The method of producing a filler for railroad frogs consisting in shaping a pair of rolled steel filler members with the inner surfaces to provide recesses for engaging and 125

fitting the outer surfaces of a frog point to provide a supporting shoulder under the sides of the point to the tip thereof and forming the outer surfaces of said rolled steel fillers to the angular formation of the guard rails on either side of the frog point.

5 6. The method of forming a frog consisting in a frog point having shoulder surfaces extending to the very tip thereof, then forming two rolled fillers with their inner surfaces shaped to provide shoulders to the very tip of the frog point, and forming the outer surfaces of the fillers to conform with the shape and angular position of the guard rails.

15 7. The method of forming fillers for a railroad frog consisting in shaping a pair of cold rolled steel fillers with the inner surfaces adapted to conform to the inner surface of the frog point and connecting rail, and cutting away the outer surfaces of the fillers to the shape and angular position of the side guard rails.

25 8. The method of forming a railroad frog filler consisting in a pair of filler members having a longitudinal wheel recess extending therein, first bending said fillers on one end to the proper angular formation, then cutting away the inner surfaces of the respective fillers to conform with the outer shape of the 35 frog point and connecting rail, and also forming the outer surfaces of the respective fillers to the angular position and contour of the inner surfaces of the guard rails of the frog.

35 9. The method of forming fillers for a railroad frog consisting in a pair of longitudinally recessed filler members, bending the filler members on one end to a desired angular shape, then planing away the inner surfaces of the respective filler members to conform 45 with the outer surface of the frog point and connecting rail, and planing of the outer surfaces to fit the contour of the guard rails.

DAVID E. ANDERSON.
